HENRY F. SCHMIDT, OF LANSDOWNE, PENNSYLVANIA, ASSIGNOR TO WESTINGHOUSE ELECTRIC & MANUFACTURING COMPANY, A CORPORATION OF PENNSYLVANIA

REDUCTION GEAR

Application filed August 29, 1931. Serial No. 560,194.

My invention relates to reduction gearing, more particularly of the marine propulsion type, and it has for an object to provide gearing which shall be compact and relatively light together with improved means of support for the pinion floating frame.

Heretofore, a floating frame type reduction gear has usually had the pinion and gear members enclosed by a suitable housing or support together with supporting means arranged at one side of the floating frame, usually below the latter, for connecting it to the housing or support and providing for tilting of the frame in a plane normal to the plane of the gear and pinion axes. With a pair of meshing gears, the force applied by the driving gear is divisible into two components, one tangential and effecting movement of the driven gear and the other a normal component tending to spread the gears apart. The spreading component gives a bending moment tending to distort the floating frame and its support and the tangential component is more or less effective in the same way dependent upon the location of the floating frame and the pinion with respect to the driven gear. In accordance with my invention, the flexible supporting means for the floating frame are effective in tension to tie the floating frame in position with respect to the driven gear bearings with the pinion in proper meshing relation so that the floating frame and its support are not subjected to bending stress. Consequently, due to the novel location and arrangement of the flexible supporting means for the floating frame such that the component forces of the gear action do not give bending moments, it is possible to make the gearing lighter. Furthermore, the fixed frame or housing for the driven gear has been modified to provide a more direct connection between the floating frame and the driven gear bearings; and, to this end, the fixed frame or housing is provided with an intermediate supporting construction or arch constituting a rigid part thereof and extending between the right and left hand helical tooth portions of the driven gear, the floating frame being connected to

this supporting construction, whereby forces tending to spread the pinion away from the driven gear are resisted in tension by the intermediate flexible supporting means for the floating frame and the supporting construction or arch of the rigid frame connected directly to such flexible supporting means. More particularly, I provide flexible webs for supporting the floating frame of a reduction gear, each of the webs having its ends connected of the floating frame and to the fixed frame having bearings for the driven gear and the webs extending between the connected ends in directions parallel to the plane of the gear and pinion axes. With webs arranged in this way, they are rendered effective in tension to resist any tendency of the pinion to spread away from the gear; and such flexible webs may be readily so arranged that no bending moment occurs which would be effective to subject the frame and its supporting structure to bending stress. A further and more particular object of my invention is, therefore, to provide reduction gearing having the aforementioned features of construction and the consequent advantages.

These and other objects are effected by my invention, as will be apparent from the following description and claims taken in connection with the accompanying drawings, forming a part of this application, in which:

Fig. 1 is a longitudinal sectional view of a double reduction gear incorporating my improvements;

Fig. 2 is a sectional view taken along the line II—II of Fig. 1;

Fig. 3 is a sectional view taken along the line III—III of Fig. 1;

Fig. 4 is a sectional view taken along the line IV—IV of Fig. 1 and showing parts of the high-speed reduction gear in plan;

Fig. 5 is a longitudinal sectional view of a single reduction gear incorporating my improvement;

Fig. 6 is a sectional view taken along the line of VI—VI of Fig. 5; and,

Fig. 7 is a sectional view taken along the 100

line VII—VII of Fig. 5 and showing interior parts of the gearing in plan.

Referring to the drawings more in detail, in Fig. 1, I show a double reduction gear including a first, or high-speed, reduction, at 10, and a second, or low-speed reduction, at 11, arranged in fixed frames or housing 12 and 13, respectively, features of the latter being more particularly hereinafter referred to.

The high-speed reduction gear includes meshing pinion and gear members 14 and 15 each having spaced right and left-hand helical tooth portions. The driven gear 15 has journals 15a carried by bearings 16 provided on a rigid frame 17 forming a part of the housing 12. The pinion 14 has journal portions 18 fitting bearings 19 provided on the floating frame 20, the floating frame being arranged to tilt in a plane normal to the plane of the axes of the pinion 14 and of the gear 15.

Referring to the novel means of support for the floating frame 20, and referring to Fig. 3, it will be noted that the floating frame 20 has its sides extending to either side of the plane of the gear and pinion axes, as indicated at 21, and such sides are provided with seats 22 arranged in a plane, or planes, normal to the plane of the gear and pinion axes. Disposed in opposed relation to the seats 22, there are seats 23 arranged parallel to the seats 22 and carried by an intermediate web or arch construction 25 forming a rigid part of the frame 17 for the driven gear.

Flexible webs 26 have terminal flanges 27 and 28 connected, respectively, to the seats 22 and 23. Hence, it will be seen that the webs 26 extend between the flanges thereof in directions parallel to the plane of the pinion and gear axes and that such webs are arranged in planes radial to the axis of tilt of the floating frame. By having the flexible webs arranged in this way, they are effective in tension to resist any tendency of the pinion to spread away from the driven gear. Furthermore due to location of flexible webs at either side of the floating frame, no moment is developed, due to the tooth action, tending to bend the frame or its supporting construction. The webs 26 deflect to provide the floating frame movement with some warping or twisting dependent upon the distance thereof from the axis of tilt.

While the flexible webs 26 are effective to connect the intermediate portion of the frame 20 to the supporting or arch construction 25 of the rigid frame 17, and while the frame itself is so constructed as to resist bending of the ends thereof outward due to the tooth action, nevertheless, it is desirable to provide additional means to resist such bending and to maintain proper meshing re-

lation of the pinion and gear teeth. In this connection, with starting of spreading of a pinion away from its gear, the spreading forces increase and vice versa. Therefore, if one end of a pinion member should tend to spread away from the gear member, the tendency would be for such spreading action to continue with the result that the gear teeth at the other end would be crowded into mesh. On this account, it is desirable to provide means associated with the ends of the frame and cooperating with the intermediate supporting webs to maintain the pinion in proper mesh and to resist any tendency of the floating frame to bend or, what is more important, to oppose any tendency to improper meshing relation. Accordingly the high-speed reduction gear at 10 has struts 30 cooperating with seats 31 provided on the floating frame 20 and with adjustable seats 32 provided at the inner ends of the screws 33 threaded to bosses 34 on the gear cover 35.

The pinion 14 is driven in the usual way by a turbine shaft 36 which has a quill drive connection with respect to the pinion 14.

In Fig. 1, the after end of the high-speed reduction gear housing 12 is provided with a hub portion 37 aligned with the hub portion 38 of the housing 13 of the low-speed reduction gearing, the hub portions being connected by a flexible sleeve construction 39. The driven gear 15 has its after journal portion 15a connected by a coupling 40 to the quill shaft 41 connected to the pinion 42 of the low-speed reduction gear, the pinion 42 meshing with the driven gear 43, and the latter having journal portions 44 fitting bearings 45 carried by the rigid frame 46. As is common practice, the forward end of the spindle of the gear 43 has a thrust collar 45' of the thrust bearing, at 46', and the after end has a coupling portion 47 for connection to the propeller shaft.

The pinion 42 is carried by a floating frame 48, which is similar in construction to and mounted in a manner similar to the floating frame 20 already referred to, that is, the intermediate portion of the floating frame 48 has lateral extensions 50 having seats 51 arranged in plane or planes at right angles to the plane of the gear and pinion axes and in opposed relation to seat or seats 52 arranged in plane or planes parallel to the seats 51, the seats 52 being provided on a supporting or arch construction 53 connected to opposite sides of the rigid frame 46 and extending between the right and left hand helical tooth portions of the driven gear. Opposed seats 51 and 52 are connected by flexible webs 54 in a manner similar to the webs 26 already referred to.

Instead of having the floating frame 48 backed up by struts acting in compression, as with the high-speed reduction gear, at

10, the floating frame 48 has tension connections 56 in the form of flexible webs having their outer termini connected to seats 57 at the ends of the floating frame 48 and 5 facing the gear bearings 45, and having their inner termini connected to seats 58 provided on the rigid fixed frame for the driven gear.

It will be noted that the flexible webs 54 10 and 56 are arranged in planes radial to the axis of tilt of the floating frame and are so disposed and connected that they act in tension to resist any tendency of the pinion to spread away from the driven gear without 15 developing any moment tending to bend or distort the pinion frame or its supporting construction. Furthermore, each of the web members extends in a direction from end-to-end parallel to the plane of the pinion 20 and gear axles, that is, at ninety degrees to the usual direction of extent of such a web member, the usual direction of extent being in a direction normal to the plane of the gear and pinion axes.

25 In Figs. 5, 6, and 7, I show a reduction gear of the single reduction type, wherein the floating frame 60 for the pinion 61 meshing with the driven gear 62 is similar in all respects to the floating frame 48 of the low-speed reduction gear shown in Fig. 1 and further detailed description thereof is unnecessary. Owing to the large size of the driven gear 62 with the large hub portion between the gear rims, it may be desirable to 30 modify the rigid supporting construction or housing somewhat over that already referred to in order to provide an intermediate support or arch extending between the right and left hand helical tooth portions of the 35 driven gear 62 for supporting the floating frame. To this end, in Figs. 5, 6, and 7, I show a gear housing having an intermediate rigid frame 63 provided with bearings 64 for the driven gear 62, and midway of the 40 length of the sides of the frame 63, there springs from such sides the arch construction 65, which may extend, in part at least, into the space between the right and left hand helical tooth portions of the driven 45 gear 62.

The intermediate portion of the arch 65 is provided with seats 66 arranged in a plane or planes normal to the plane of the gear and pinion axes and opposed respectively by seats 67 provided at the sides of the floating frame 60, and the seats are connected by flexible webs 68 in a manner similar to that hereinbefore referred to.

From the foregoing, it will be apparent 50 that I have devised a reduction gear which may be made very light and strong for the power transmitted. One of the principal features contributing to these advantages is the arrangement and connections of the flexible supporting elements for the floating

frame. These flexible supporting elements are connected to the fixed frame having bearings for the driven gear and to the floating frame so as to be effective in tension to resist any tendency of the pinion to spread 70 away from the driven gear. The ends of the floating frame may be restrained either by struts or by flexible tension elements, such restraint being desirable to prevent disturbance of proper meshing relation and to resist bending of the floating frame due to tooth pressure. By having flexible connections at either side of the floating frame, the pinion is held in meshing relation by balanced tension force and there is no unbalanced force setting up a bending stress in 75 the floating frame or its mounting. Consequently, the gearing, and particularly the floating frame and the supporting construction therefor, may be made lighter and 80 stronger. In addition to the novel mode of mounting the floating frame, strength and lightness are further promoted by the structure of the rigid frame for the driven gear, the latter having formed, as an integral and 85 rigid part thereof, an intermediate web or arch construction constituting a support for the intermediate flexible web elements of the floating frame. Hence, there is a very direct connection tying of the floating frame and 90 the gear bearings together, the connection being from the floating frame, through the tension webs, to the intermediate partition or arch construction forming a part of the 95 rigid frame of the driven gear and thence to the bearings of the latter.

While I have shown my invention in several forms, it will be obvious to those skilled in the art that it is not so limited, but is susceptible of various other changes 105 and modifications, without departing from the spirit thereof, and I desire, therefore, that only such limitations shall be placed thereupon as are imposed by the prior art or as are specifically set forth in the appended claims.

What I claim is:

1. In a reduction gear, meshing pinion and gear members, a rigid frame having bearings for the gear member and provided with an arch springing from opposite sides thereof and midway of the length of the latter, a floating frame for the pinion disposed oppositely to the central portion of the arch, and flexible connecting means between the central portion of the arch and the floating frame.

2. In a reduction gear, meshing pinion and gear members, each having spaced right and left-hand tooth portions, a rigid frame having bearings for the gear member and provided with an arch construction springing from opposite sides thereof and extending between the right and left-hand tooth portions of the gear member, a floating

frame for the pinion, and flexible supporting means connected to the floating frame and to said arch.

3. In a reduction gear, meshing pinion and gear members, a fixed frame having bearings for the gear member, a floating frame having bearings for the pinion member, and members having their opposite ends connected to the fixed frame and to the floating frame for supporting the latter from the former, said members extending between their end connections, parallel to the common plane of the gear pinion member axes and crosswise of the space between planes including the pinion and gear member axes and normal to the common plane of said axes, whereby said members are effective in tension to resist spreading of the pinion member away from the gear member, and said members being capable of flexing to provide for floating or rocking movement of the floating frame to balance tooth pressures.

4. In a reduction gear, meshing pinion and gear members, a fixed frame having bearings for the gear member, a floating frame having bearings for the pinion member, and supporting means for the floating frame including a plurality of web members having their opposite ends connected to the fixed frame and to the floating frame and extending crosswise of the space between planes including the pinion and gear member axes and normal to the common plane of said axes, said web members being disposed substantially radially with respect to the axis of tilt of the floating frame so that they may flex to provide for floating or rocking movement of the floating frame to balance tooth pressures.

5. In a reduction gear, meshing pinion and gear members; a fixed frame having bearings for the gear member; a floating frame having bearings for the pinion member; and a pair of flat web members arranged substantially in the plane of the pinion and gear member axes, having opposite ends thereof connected to the fixed frame and to the floating frame, and extending, between their end connections, crosswise of the space between planes including the pinion and gear member axes and normal to the common plane of said axes.

6. In a reduction gear, meshing pinion gear members; a fixed frame having bearings for the gear members; a floating frame having bearings for the pinion member; and first and second pairs of flat web members having their opposite ends connected to the fixed frame and to the floating frame for supporting the latter from the former and extending, between their end connections, crosswise of the space between planes including the pinion and gear member axes and normal to the common plane of said

axes; said first pair of web members being arranged substantially in the common plane of the pinion and gear member axes and said second pair of web members being arranged in a plane substantially normal to said common plane.

7. In a reduction gear, meshing pinion and gear members; a fixed frame having bearings for the gear member; a floating frame having bearings for the pinion member; and a pair of web members having their opposite ends connected to the fixed frame and to the floating frame for supporting the latter from the former; said web members being disposed at either side of the axis of the pinion member, arranged substantially in a plane normal to the pinion member axis, and extending crosswise of the space between the planes including the pinion and gear member axes and normal to the common plane of said axes.

In testimony whereof, I have hereunto subscribed my name this 24th day of August, 1931.

HENRY F. SCHMIDT.
